(57) **CLAIM**

The ornamental design for a wrist-wearable liquid dispenser, as shown and described.

DESCRIPTION

FIG. 1 is a perspective view of a wrist-wearable liquid dispenser, showing my new design in a worn configuration; FIG. 2 is an enlarged perspective view thereof; FIG. 3 is a top perspective view thereof, illustrated in an unworn configuration;

FIG. 4 is an exploded top perspective view of FIG. 3; FIG. 5 is an exploded bottom perspective view of FIG. 4; FIG. 6 is an exploded top plan view of FIG. 4;

FIG. 7 is an exploded bottom plan view of FIG. 4; FIG. 8 is an exploded front elevational view of FIG. 4, the rear elevational view being a mirror image thereof;

FIG. 9 is an exploded left-side elevational view of FIG. 4; FIG. 10 is an exploded right-side elevational view of FIG. 4; and,

FIG. 11 is an exploded cross-sectional view thereof, taken along line 11-11 of FIG. 6.

The broken lines showing a person's arm in FIG. 1 depict environmental matter and form no part of the claimed design.
